Primary Examiner — Ricky Pham*(74) Attorney, Agent, or Firm* — Notaro, Michalos & Zaccaria P.C.(57) CLAIM

The ornamental design for a fry basket, as shown and described.

DESCRIPTION

FIG. 1 is a top, rear, right perspective view of a fry basket showing my design therefor;

FIG. 2 is a top, front, left perspective view with the handle in the folded position;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

Throughout the drawings, broken lines show environment only and form no part of the claimed design.

1 Claim, 8 Drawing Sheets See application file for complete search history.
